[57] CLAIM

The ornamental design for a electronic calculator with solar cell, as shown and described.

DESCRIPTION

FIG. 1 is a top, front and right side perspective view of an electronic calculator with solar cell according to our design;

FIG. 2 is a top plan view thereof;

FIG. 3 is a bottom plan view thereof;

FIG. 4 is a front elevational view thereof;

FIG. 5 is a rear elevational view thereof; and,

FIG. 6 is a right side elevational view, the left side elevational view being a mirror-image thereof.
